United States Patent Office

Des. 193,689
Patented Sept. 25, 1962

193,689

BOTTLE FOR JUICE OR THE LIKE

Henry Wish, Eastchester, N.Y., assignor to Lucky Wish Products, Inc., Holbrook, N.Y., a corporation of New York

Filed Feb. 12, 1962, Ser. No. 68,765

Term of patent 7 years

(Cl. D58—9)

FIG. 1 is a top plan view of a bottle for juice or the like, embodying my new design;

FIG. 2 is a side elevational view thereof taken from the left of FIG. 1 with the closure open; and

FIG. 3 is a fragmentary view of the top portion thereof taken from the right of FIG. 2.

I claim:

The ornamental design for a bottle for juice or the like, substantially as shown.
